APPARATUS FOR AND METHOD OF PULSE KEYING

Irving Wolff, Merchantville, N. J., assignor to
Radio Corporation of America, a corporation of
Delaware

Application December 30, 1937, Serial No. 182,418

11 Claims. (Cl. 250—17)

1

My invention relates to an apparatus for and a method of pulse keying and more specifically to a keying system in which the marking pulses are of extremely short duration.

I am aware that numerous high speed mechanical keying systems have been devised for forming telegraphic characters. It has also been proposed to use multivibrators for generating a keying pulse. The multivibrator is used to establish currents of saw-tooth wave form. These currents are applied to a limiter which selects the peaks and thereby establishes a short marking impulse. In systems in which small keying powers are required, the multivibrator type keying may suffice. When larger powers and extremely short marking pulses are required, the problem is not as easily solved. For example, in systems which require marking pulses of the order of a microsecond or less duration and substantial amounts of power, it becomes increasingly difficult to shorten the pulses and equally difficult to efficiently amplify the pulses.

I propose to apply the initial pulses to a device which not only efficiently amplifies the pulses but also shortens the duration of the pulse. The device in certain respects resembles a resistance coupled amplifier in which inductors are substituted for the resistances, and in which only the positive pulses are transmitted. Keying or marking devices of this type are used to start and stop oscillators, amplifiers, or modulators. In practice, my invention may be applied to obstacle detectors operating on the radio echo principle, radio operated altimeters, television synchronizing impulses and the like.

One of the objects of my invention is to provide means for generating keying pulses of very short duration and substantial amplitude.

Another object is to provide means for efficiently amplifying pulse currents having a duration of the order of microseconds.

An additional object is to provide means for amplifying pulse currents of short duration and simultaneously decreasing the pulse duration.

A still further object is to provide means for keying an obstacle detector transmitter by marking pulses of extremely high periodicity.

My invention may be best understood by reference to the accompanying drawing which is a schematic diagram. A multivibrator 1, which generates currents of saw-tooth wave form 3, is connected through a transformer 5 to a vacuum tube amplifier 7. The primary 9 of the transformer 5 may be shielded from the secondary 11 by an electrostatic screen 13. The secondary 11 is preferably of low impedance and, together with the input capacity of the amplifier 7, may be arranged to resonate at substantially the period of the applied pulse 15. The grid electrode 14 of the

2

amplifier 7 is biased negatively with respect to cathode 16 by a biasing battery 17.

The anode of the amplifier 7 is connected through a low impedance inductor 19 to the positive terminal of a B battery 21. The negative terminal of the battery 21 is connected to the positive terminal of the biasing battery 17, cathode 16, and ground. The inductor 19 is coupled through a blocking capacitor 23 to the grid 24 of a second amplifier 25. The grid 24 is biased negatively with respect to cathode 26 by a grid resistor 27 which is connected to the negative terminal of the biasing battery 25. The natural period of the inductor 25 and associated capacities is preferably of the order of the natural period of the applied pulses 29.

The anode of amplifier 25 is connected through a low impedance inductor 31 to the positive terminal of the B battery 21. A potentiometer 33 is shunted across the inductor 31. The inductor is coupled through a network 35 and a serially connected source 37 of biasing voltage to key an oscillator 39 or the like. The output of the oscillator is applied to an antenna 41 or other load circuit.

Having described the circuit, the mode of operation will be set forth. In the condenser charging circuit of the multivibrator, pulses of current are available. These discrete pulses 15 are applied to the primary 9 of the transformer 5. The pulses 15 are suitably phased by the transformer 11 so that the grid 14 is driven positive with respect to its cathode 16.

The amplified positive pulses act on the inductor 19 and, due to its differentiating effect in a mathematical sense, create negative pulses during the rise and positive pulses during the fall of current of pulses 18. Due to the action of the resonant circuit, including inductor 19 and its associated capacities in tubes 7 and 25, and the shunt resistor 27 and grid circuit losses in tube 25, a highly damped wave train 29 is created. It will be observed that the duration of the first negative and first positive portions of the wave train 29 is substantially equal to the duration of the applied positive pulse. Thus the original pulse duration is decreased.

The wave train 29 is applied through the blocking capacitor 23 to the input of the second amplifier 25. This amplifier is biased so that its output current is near cut-off. Because of this bias, the first positive pulse of the wave train 29, and sometimes the following positive pulse, will actuate the amplifier 25. The inductor 31 will have established therein amplified wave trains 30 which are highly damped due to the resistance of the potentiometer 33, and the energy absorbing characteristics of the oscillator input. The duration of the positive pulses of the wave trains 30 will again be shortened. These positive pulses 32 of the wave trains 30

will overcome the bias 37 which normally prevents the oscillator 39 from functioning and will abruptly key the oscillator. The oscillator 39, thus keyed, will generate oscillatory currents 34 during a portion of the first positive pulse duration. The pulse duration may be adjusted from a fraction of a microsecond to several microseconds. The keying pulses may follow each other at the required rate of keying.

It should be understood that the transformer 5 may be replaced by an inductor, blocking capacitor and grid resistor. In order to effectively match impedances, the inductors may be used as autotransformers.

I claim as my invention:

1. A pulse generator device including in combination a source of rapidly varying currents, means for transforming said currents into highly damped wave trains, means for amplifying the positive pulses of said wave trains, and means for applying the amplified positive pulses to an output circuit.

2. A pulse keying device for a transmitter including in combination a source of pulses, means for transforming said pulses into highly damped wave trains, means for amplifying the first positive pulse of said wave train, means actuated by said amplified positive pulse for creating a second highly damped wave train, and means for applying the first positive pulse of said second highly damped wave train to key said transmitter.

3. A keying device including in combination a circuit to be keyed, a source of discrete pulses, means for converting said discrete pulses into a first series of highly damped wave trains, means for amplifying the first positive pulse of said wave trains, means for deriving from said amplified positive pulses a second series of highly damped wave trains, means for amplifying the first positive pulse of each of said second series of highly damped wave trains, means for deriving from said last-mentioned amplified positive pulses a third series of highly damped wave trains, and means for applying the first positive pulse of said third series of highly damped wave trains to said circuit to be keyed.

4. A keying device including in combination a keying circuit, a source of current pulses, means for transforming said pulses into series of wave trains, means for highly damping said wave trains, said trains including negative phased pulses and positive phased pulses, means for amplifying the first of each of said positive pulses, means responsive to said positive pulses for creating a second series of wave trains, means for highly damping said second series of wave trains, said second series of wave trains including negatively phased pulses and positive phased pulses and means for applying the first of each of said last-mentioned positively phased pulses to a keying circuit.

5. The method of establishing and applying keying pulses to a load circuit which comprises, generating discrete discharge currents, converting said discrete discharge currents into discrete pulses, transforming said discrete pulses into wave trains including highly damped negatively and positively phased pulses, amplifying said positively phased pulses, and applying the first of said amplified positive pulses to said load circuit.

6. The method of establishing keying pulses of extremely short duration which comprises generating discrete discharge currents, converting said discrete discharge currents into discrete pulses, transforming said discrete pulses into highly damped oscillatory currents, amplifying the first positively phased oscillation, converting said amplified oscillation into a second series of highly damped oscillatory currents, and deriving from said last oscillatory currents a positively phased pulse of extremely short duration.

7. A pulse keying device including a source of discrete pulses of current of a single phase, means for converting each of said pulses of single phase into currents of positive and negative phases forming highly damped wave trains, means for selectively amplifying currents of the first positive phase of each of said wave trains, and means for creating from said positive phase currents a second current having negative and positive phases of less duration than said first mentioned currents of positive and negative phases.

8. A pulse keying device including a source of discrete pulses of current of a single phase, means for converting each of said pulses of single phase into highly damped waves including currents of positive and negative phases, means for selectively amplifying currents of the first positive phase of each of said waves, and means for creating from said positive phase currents a second current having negative and positive phases of greater amplitude and less duration than said first mentioned currents of positive and negative phases.

9. A pulse keying device including a source of discrete pulses of current of substantially uniform duration, means for converting said discrete pulses of currents into highly damped waves including positively and negatively phased currents, the period of said two phases being of substantially the same duration as said discrete pulses, and means for selecting in each of said waves the first positive phase currents and excluding said negatively phased currents whereby the duration of said selected phases is less than the duration of said discrete pulses.

10. A pulse keying device including a source of discrete pulses of current of substantially uniform duration, means for converting said discrete pulses of currents into highly damped wave trains including positively and negatively phased currents, the period of said two phases being of substantially the same duration as said discrete pulses, means for selecting the first of the positively phased currents of each of said wave trains and excluding said negatively phased currents whereby the duration of said selected phases is less than the duration of said discrete pulses, means for amplifying said positively phased currents, and means for establishing currents of positive and negative phases of a duration controlled at least in part by said first mentioned positively phased currents.

11. A pulse amplifier including a source of positive pulse voltages, means for converting said positive pulse voltages into a highly damped wave train having negative and positive voltage peaks, and means for amplifying the first positive peak without amplifying negative peaks of said wave train.

IRVING WOLFF.
